(57) **CLAIM**

The ornamental design for an environmental sampling device as shown and described.

DESCRIPTION

FIG. 1A is a front and top perspective view of an environmental sampling device in accordance with the present design, the environmental sampling device including a top section in screw thread engagement with a bottom section;

FIG. 1B is a rear and top perspective view of the environmental sampling device of FIG. 1A;

FIG. 1C is a rear and bottom perspective view of the environmental sampling device of FIG. 1A;

FIG. 1D is a top plan view of the environmental sampling device of FIG. 1A;

FIG. 1E is a bottom plan view of the environmental sampling device of FIG. 1A;

FIG. 1F is a right side elevational view of the environmental sampling device of FIG. 1A, which is also representative of the left side elevational view;

FIG. 1G is a rear elevational view of the environmental sampling device of FIG. 1A;

FIG. 2A is a front and top perspective view of just the top section of the environmental sampling device of FIG. 1A;

FIG. 2B is a rear and top perspective view of just the top section of the environmental sampling device of FIG. 1A;

FIG. 2C is a right side elevational view of just the top section of the environmental sampling device of FIG. 1A, which is also representative of the left side elevational view of the top section;

FIG. 2D is a rear elevational view of just the top section of the environmental sampling device of FIG. 1A;

FIG. 3A is a front and top perspective view of just the bottom section of the environmental sampling device of FIG. 1A;

FIG. 3B is a rear and top perspective view of just the bottom section of the environmental sampling device of FIG. 1A;

FIG. 3C is a rear and bottom perspective view of just the bottom section of the environmental sampling device of FIG. 1A;

FIG. 3D is a top plan view of just the bottom section of the environmental sampling device of FIG. 1A;

FIG. 3E is a bottom plan view of just the bottom section of the environmental sampling device of FIG. 1A;

FIG. 3F is a right side elevational view of just the bottom section of the environmental sampling device of FIG. 1A, which is also representative of the left side elevational view of the bottom section; and,

FIG. 3G is a rear elevational view of just the bottom section of the environmental sampling device of FIG. 1A.
